UNITED STATES PATENT OFFICE.

FRANK EISENHARD, OF ALLENTOWN, PENNSYLVANIA, ASSIGNOR OF ONE-HALF TO
ELLWOOD S. ADAMS, OF ALLENTOWN, PENNSYLVANIA.

SCREW DRIVER.

Application filed June 26, 1920. Serial No. 391,927.

To all whom it may concern:

Be it known that I, FRANK EISENHARD, a citizen of the United States, residing at Allentown, in the county of Lehigh and State of Pennsylvania, have invented a new and useful Screw Driver, of which the following is a specification.

This invention relates to the class of tools, and more particularly to a novel form of screw driver, it being the primary object of the invention to provide a novel form of screw driver, wherein the operator may grasp the handle of the driver at all times, during the operation of driving a screw, thus eliminating the necessity of releasing his grip on the handle.

A further object of the invention is to provide a device of this character having a hollow handle, to provide a compartment for supporting various sized driving blades, to adapt the device for various usages.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a side elevational view partly in section to disclose the driving blade receiving end of the device.

Figure 2 illustrates a longitudinal sectional view through the driver.

Figure 3 illustrates a sectional view taken on line 3—3 of Figure 2; and

Figure 4 illustrates an end elevational view of the driver.

Referring to the drawing in detail, the reference character 5 designates the handle portion of the screw driver, the same being shown as hollow to provide a blade receiving compartment 6, there being a removable cover 7 provided on the upper extremity of the handle 6, to permit of easy access to the compartment 6.

The lower extremity of the handle portion 5 is reduced to receive the collar 8 which has its lower extremity notched to provide a plurality of teeth 9, which teeth

are designed to cooperate with the teeth 10 formed on the blade receiving socket 11 which is supported within the tubular member 12, that is secured to the collar 8 as by means of the set screw 13, which passes through registering openings formed in the tubular member 12, collar 8 and reduced portion of the handle.

This tubular member 12 is relatively long to permit of movement of the socket member 11 longitudinally thereof, so that the teeth 9 and 10 may be brought into cooperative relation with each other to connect the socket member 11 and handle, so that movement of the handle will be transmitted to the socket member 11 and blade supported thereby, the blade being of a construction to permit one extremity thereof to be inserted in the socket member 11.

Shoulders indicated at 14 cooperate with the shoulders 15 of the tubular member 12 to restrict movement of the socket member 11 with relation to the tubular member 12. The lower extremity or reduced portion of the handle 5, is provided with a cut out portion extending from the extreme lower end thereof and terminating at a point in spaced relation with the lower wall of the compartment 6, and is provided to accommodate the coiled spring 16 which has one of its ends seated on the base 17 of the socket member 11, the upper end thereof contacting with the upper wall of the cut out portion, so that the spring will normally force the teeth 9 and 10 out of cooperative relation with each other to permit the handle portion 5 to be rotated with relation to the socket member 11.

In the operation of the device, assuming that a driving blade is positioned in the socket member 11, and the blade is positioned on a screw to cause the same to be screwed home, it is obvious that when pressure is exerted on the handle 5, the teeth 9 are forced between the teeth 10 of the socket member 11, and slight rotation of the handle 5 causes the socket member to be rotated to rotate the screw under operation.

It is obvious that when pressure on the handle 5 is relieved, the teeth 9 and 10 are moved out of engagement with each other by means of the spring 16, and the handle may now be rotated in the opposite direction, or to a position whereby the handle

may be again depressed and rotated, resulting in the rotation of the screw, in one direction.

Having thus described the invention, what is claimed as new is:—

A screw driver comprising a hollow handle having a reduced end section, said reduced end section being hollowed out to provide a coiled spring housing, a collar 10 positioned on the hollow reduced portion of the handle and having teeth formed in its lower edge, a blade receiving socket member positioned over the reduced portion of the handle and having teeth adapted to mesh 15 with the teeth of the collar, said socket member having a shoulder providing a rest for one end of a coiled spring, said blade receiving socket member having a shoulder formed on the periphery thereof, and a tubu-

lar member embracing the collar and a portion of the blade receiving socket member, said tubular member having shoulders co-operating with the shoulders of the blade receiving socket member to restrict movement of the blade receiving socket member, means for securing the tubular member to the handle, and a coiled spring disposed within the hollow portion of the reduced end of the handle for normally urging the teeth out of engagement.

In testimony that I claim the foregoing as my own, I have hereto affixed my signature in the presence of two witnesses.

FRANK EISENHARD.
